CLAIM

The ornamental design for a trocar introducer device as shown and described.

DESCRIPTION

FIG. 1 is a top-front-left perspective view of a trocar introducer device in accordance with the present design; FIG. 2 is a bottom-rear-right perspective view thereof; FIG. 3 is a top view thereof;

FIG. 4 is a bottom view thereof;

FIG. 5 is a left-side elevational view thereof;

FIG. 6 is a right-side elevational view thereof;

FIG. 7 is a front-plan view thereof; and,

FIG. 8 is a back-plan view thereof.

The broken lines shown in FIGS. 1, 3, 5, and 7 illustrate environment that form no part of the claimed design.

1 Claim, 4 Drawing Sheets
